UNITED STATES PATENT OFFICE

151,188

DESIGN FOR A STOOL OR SIMILAR ARTICLE

Edward V. Price and Veronica E. Price,
Van Nuys, Calif.

Application June 19, 1946, Serial No. 130,862

Term of patent 14 years

(Cl. D15—8)

To all whom it may concern:

Be it known that we, Edward V. Price and Veronica E. Price, citizens of the United States and residents of the city of Van Nuys, in the county of Los Angeles and State of California, have invented a new, original, and ornamental Design for a Stool or Similar Article, of which the following is a specification, reference being had to the accompanying drawing, forming part thereof, in which:

Fig. 2 is a perspective view similar to Fig. 1 but showing the concealed drawer in its extended or open position to provide a foot rest.

Fig. 3 is a top plan view of the stool, as shown in Fig. 1.

We claim:

The ornamental design for a stool or similar article, substantially as shown and described.

EDWARD V. PRICE.
VERONICA E. PRICE.
